UNITED STATES PATENT OFFICE

109,677

DESIGN FOR A DECORATIVE GRILLE FOR AN AUTOMOBILE RADIATOR

George Snyder, Detroit, Mich., assignor to General Motors Corporation, Detroit, Mich., a corporation of Delaware

Application October 9, 1937, Serial No. 72,098

Term of patent 3½ years

To all whom it may concern:

Be it known that I, George Snyder, a citizen of the United States and a resident of Detroit, county of Wayne, and State of Michigan, have invented a new, original, and ornamental Design for a Decorative Grille for an Automobile Radiator, of which the following is a specification, reference being made to the accompanying drawings, forming a part thereof.

Figure 1 is a front elevational view of a deco-

rative grille for an automobile radiator showing my novel design.

Figure 2 is a side elevational view of the novel design.

Figure 3 is a partial sectional view on the line 3—3 of Figure 2.

I claim:

The ornamental design for a decorative grille for an automobile radiator as shown.

GEORGE SNYDER.
